UNITED STATES PATENT OFFICE.

HUGO G. HESS, OF CINCINNATI, OHIO.

DESIGN FOR A CASING FOR INDICATORS.

SPECIFICATION forming part of Design No. 26,426, dated December 22, 1896.

Application filed October 29, 1896. Serial No. 610,511. Term of patent 14 years.

To all whom it may concern:

Be it known that I, HUGO G. HESS, a citizen of the United States, residing at Cincinnati, in the county of Hamilton and State of 5 Ohio, have invented and produced a new and original Design for a Casing for Time and Result Indicators for Race-Tracks, of which the following is a specification.

The accompanying drawing, which forms a 10 part of this specification, is a perspective view of a race-track time and result indicator embodying my design.

The leading feature of my design consists in the novel shape or configuration of the 15 casing shown, to wit: The fore end of the casing is rectangular and provided with two or more rectangular-shaped windows or sight-openings. A vertical straight bar or partition intervenes between the several fore windows 20 or sight-openings, terminating at top and bottom thereof. The sides of the casing are flat with their fore and rear ends perpendicular and at right angles to their bottom edges, and their upper edges horizontal a short distance 25 rearward from their fore ends, then shouldered slightly with a short perpendicular line downward, then horizontal again almost half-way rearward, then inclined at an angle of forty-five (45°) degrees, more or less, downward to about mid-depth, and then horizontal the remainder of their lengths rearward. Along 30 said irregular-outlined or peculiar-shaped upper edges of the sides of the casing are the flanged sides of a folding hinged lid 35 or top, which sides conform to said upper edges of the casing sides, and the forwardly-folding lid being made flat throughout and horizontally parallel to the bottom of the casing, except about mid-length, where it inclines to conform or correspond to the angle 40 of its said sides and the inclined portions of the upper edges of the casing sides. Surmounting the fore ends of the casing sides is a horizontal flat stationary rectangular-shaped

strip to which the folding lid is hinged. The 45 bottom of the casing is flat and has longitudinal strips or rests at either side, which strips are rectangular in cross-section.

A represents the horizontal flat bottom or base, having the flat resting-strips *a a*, flat 50 vertical sides *B B*, and intermediate vertical longitudinal partition *C*, at either side of which latter is a rectangular-shaped window or sight-opening *c*. At the fore end of the sides *B* is a flat rectangular-shaped cross-bar 55 *D*, and surmounting said sides *B* is a folding hinged lid *E*, composed of two sections or divisions having flat tops and pendent flanged sides *e*. Intermediate the opposite ends of the lid it is made at an inclination downward toward the rear, wherein the hinged joint between the fore and rear divisions or sections thereof occurs.

The two sides *B* of the casing have their fore and rear ends made perpendicular and 65 their upper edges horizontal at *b* a short distance rearwardly, then perpendicular at *b'* a short distance downwardly, then horizontal at *b''* almost half-way rearwardly, then at an 70 inclination of forty-five (45°) degrees, more or less, at *b'*, then horizontal at *b''* the remainder of their lengths rearwardly. The sides *e* of both sections of the lid conform exactly 75 along their top and bottom edges to the irregular outline just described of the upper edges of the casing sides *B*, thus giving the top of the machine-casing a fall or depression at the rear end somewhat lower than it is at its fore portion, which readily presents itself to the eye at all times.

I claim—

The design for a casing for a time and result indicator for race tracks or courses, substantially as herein shown and described.

HUGO G. HESS.
